COMPOSITE RIBBON

Paul U. Klein, Bronx, N. Y.

Application June 7, 1947, Serial No. 753,203

5 Claims. (Cl. 154—53.6)

1

This invention relates to ribbon constructed of a plurality of different strip or strand elements arranged in edge to edge relationship and united by an adhesive agent adhering and securely binding the various strips or strands and, further, wherein the strips or strands are kinked or folded to produce longitudinally spaced or transversely arranged corrugations throughout the length of the ribbon. Still more particularly, my invention deals with a composite ribbon, wherein the cellophane strips employed are folded to form side pockets and extending flanges for reception of rayon strands and tinfoil and/or tinsel strands.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is an edge and perspective view of a short strip of ribbon diagrammatically illustrating the structure and contour thereof.

Fig. 2 is an edge view of a ribbon showing a slight modification of the structure as seen in Fig. 1; and

Fig. 3 is a view similar to Fig. 2 showing another modification.

In producing composite ribbon of the type and kind under consideration, I employ two or three strip or strand elements such, for example, as rayon or equivalent strands, cellophane or other strips of this general type and kind, in connection with which may also be employed metallic strands or what is generally termed and identified as tinfoil and/or tinsel. In each instance, the separate elongated strand or striplike elements may be formed of different colors. However, in most ribbons, I have found it desirable from a standpoint of effect to use substantially clear or transparent rayon strands and to contribute color to the ribbon by the color of the cellophane and also by the color of the tinfoil and/or tinsel. I prefer the latter in colors contrasting to but in harmony with the cellophane, thus producing in the ribbon multiple color effects. As and when two cellophane strips are employed, these may be in the same or in contrasting colors, thus producing multi-color effects in the resulting product.

In Fig. 1 of the drawing, I have illustrated what might be well termed an exaggerated showing of the edge and longitudinal contour of a ribbon, the various parts of the ribbon being exaggerated as to size for simplicity in the illustration. In

2

this figure, 10 and 11 represent two similar bands of folded cellophane or similar material and 13 a center band of rayon or similar material.

Each band 10 and 11 comprises a wide strip of cellophane folded inwardly upon itself, as seen at 14 and 15, respectively, and then inwardly to form a short flange 16 and 17 respectively, and then outwardly to form a long flange 18 and 19 respectively, the latter extending beyond the fold to form a pocket as at 20, 21 for the reception of a tinfoil or tinsel strip or strand 22, 23, respectively.

The inner folds 16 and 17 form pockets to receive a few of the side edge strands of the rayon band 13. This construction produces a relatively wide center single lay of the cellophane strip forming the bands 10 and 11, as seen at 24, 25 respectively. The reverse folds form band portions of three ply-thickness as at 26, 26' on the band 10 and 27, 27' on the band 11. Whereas the protruding edges 19 and 20 of the strips with the tinsel thereon produce a two-ply thickness or an effect where the single thickness of the cellophane sheet is shaded by the tinfoil and tinsel, thereby producing in each complete band 10 and 11 three distinct densities of color and, in fact, four densities of color are produced, in that the lay of the rayon within the folds 16 and 17 will modify the shade of the band portions 26', 27'.

The advantage of this construction, aside from producing a relatively strong ribbon, lies in the fact that a more substantial binding between the separate bands and the bands and the tinfoil and tinsel is established by virtue of the overlapped relationship of the parts. The resulting ribbon is also creased or folded transversely to produce corrugations, as at 28 in Fig. 1 which aid in supporting the bands or elements of the bands in edge to edge and overlapped relationship and in enhancing the appearance of the resulting ribbon.

In Fig. 2 of the drawing, I have shown a slight modification of the structure shown in Fig. 1, wherein the center rayon band 13' is sub-divided centrally by a tinfoil or tinsel strand 29, otherwise the bands 10' and 11' are of the same construction as the bands 10 and 11 and, for this reason, no further detail description thereof will be given.

Fig. 3 modifies the structure shown in Fig. 2 in incorporating between two bands 10'', 11'', bands identical to the bands 10, and 11 and 10', 11', a center cellophane band 30 having two folded edge portions 31, 32 similar in all respects to the folded edges 16 and 17 and arranged within these folded edges and the folded edges 16', 17' of the bands

10" and 11" are two rayon bands 33, 34, each sub-divided centrally by a tinfoil or tinsel strip or strand 35, 36, respectively. In other words, the ribbon, as disclosed in Fig. 3, simply adds one additional cellophane band and one additional rayon band to the complete structure and, if the cellophane and rayon bands are of the same size as that employed in Fig. 2, size being considered from the standpoint of width, then the ribbon of Fig. 3 will be wider than the ribbon of Fig. 2.

In Figs. 1 and 2, the bands 10, 11; 10', 11' may be of the same or different colors; whereas in Fig. 3 all of the cellophane bands may be of the same or different colors, or two bands of one color and the other band of a contrasting color. In referring to colors or contrasting colors, this may be shades of a common color. In all instances, the tinfoil or tinsel strips or strands will be of contrasting colors with respect to the cellophane bands and may be contrasting to each other, particularly where three or more of the strands are employed.

In referring to rayon and cellophane, reference is here made to strands or strips of contrasting characteristics and having at least slightly different properties. The strand band may comprise threadlike strands of any suitable texture or a combination of strands such for example as the strands of the plastic group, as well as those of the cotton and other materials. In like manner, in referring to cellophane strips, these strips may be of thin sheetings of any type or kind that will produce a relatively soft and pliable effect in the resulting ribbon to adapt the same for tying while at the same time giving strength to the resulting ribbon to stand up under longitudinal stresses or strains. The use of the tinfoil and/or tinsel, which produces a border or edging or a striping in the resulting ribbon is, of course, optional.

The cement or binding agent employed forms a film-like deposit on the strands and strips of the ribbon and this deposit is water soluble having the property of establishing a binding between ribbon ends in decorating a package when the film is moistened and, with some types of paper wrapper, the adhesive properties are sufficient to retain the ribbon against displacement from the wrapping.

The strips which have been generally classified as cellophane may comprise any cellulosic base material which would be suitable for the intended purpose. In the same sense, the rayon strands may be classified as synthetic fibrous materials and, in some instances, these strands may also be of a cellulosic base. It will be apparent that, in all forms of construction shown, the cellophane or strip of cellulosic base material has, at its outer side edges of the ribbon, extending flange portions and upon these flange portions the tinfoil or tinsel strands are arranged. It will be also seen that another distinctive feature in the ribbon lies in the fact that adjacent edge portions of two cellophane strips or bands have the folds, in which part of the rayon strands are disposed, thereby establishing a secure binding between the rayon and cellophane and preventing any possible parting of the strands, as might sometimes be experienced where the edge of a rayon band simply abuts the adjacent edge of a cellophane strip or band.

Having fully described my invention what I claim as new and desire to secure by Letters Patent is:

1. A composite ribbon-like product of the character described, comprising a plurality of transversely arranged contrasting bands, at least two of said bands comprising strips of a cellulosic base material, another band comprising a plurality of strands of synthetic material, the strips of the first bands having portions folded one upon the other, the strips of outer bands terminating at side edges in outwardly extending flanges defining side edge portions of the resulting ribbon, means comprising a cement forming a coating uniting the strands of the first named band and said bands in forming the ribbon, and edge portions of the first named bands adjacent the second named band having folds, within which part of the strands of the second named band are arranged.

2. A composite ribbon-like product of the character described, comprising a plurality of transversely arranged contrasting bands, at least two of said bands comprising strips of a cellulosic base material, another band comprising a plurality of strands of synthetic material, the strips of the first bands having portions folded one upon the other, the strips of outer bands terminating at side edges in outwardly extending flanges defining side edge portions of the resulting ribbon, means comprising a cement forming a coating uniting the strands of the first named band and said bands in forming the ribbon, edge portions of the first named bands adjacent the second named band having folds, within which part of the strands of the second named band are arranged, the side edge portions of the first named bands inwardly of the flanges comprising three-ply of the strip forming said bands, and metallic strands at outer edge portions of the ribbon and disposed on said flanges.

3. A composite ribbon-like product of the character described, comprising a plurality of transversely arranged contrasting bands, at least two of said bands comprising strips of a cellulosic base material, another band comprising a plurality of strands of synthetic material, the strips of the first bands having portions folded one upon the other, the strips of outer bands terminating at side edges in outwardly extending flanges defining side edge portions of the resulting ribbon, means comprising a cement forming a coating uniting the strands of the first named band and said bands in forming the ribbon, edge portions of the first named bands adjacent the second named band having folds, within which part of the strands of the second named band are arranged, the side edge portions of the first named bands inwardly of the flanges comprising three-ply of the strip forming said bands, metallic strands at outer edge portions of the ribbon and disposed on said flanges, and a metallic strand disposed centrally of the second named band.

4. A ribbon of the character described comprising alternate bands of synthetic fibrous material and a cellulosic base material arranged transversely of the ribbon, the first named band comprising a multiplicity of strands arranged side by side, the second named bands having edge portions overlying part of the strands of the first named band, a coating on the ribbon uniting the strands of the first named band and said band with the second named bands, and the second named bands terminating at side edge portions of the resulting ribbon in reverse folds.

5. A ribbon of the character described comprising alternate bands of synthetic fibrous material

and a cellulosic base material arranged transversely of the ribbon, the first named band comprising a multiplicity of strands arranged side by side, the second named bands having edge portions overlying part of the strands of the first named band, a coating on the ribbon uniting the strands of the first named band and said band with the second named bands, the second named bands terminating at side edge portions of the resulting ribbon in reverse folds, said folds having outwardly extending flange portions, metallic strands arranged upon said flange portions, and other metallic strands forming part of the first named band.
